UNITED STATES PATENT OFFICE.

LARS J. LARSON, OF SEATTLE, WASHINGTON.

DOOR LOCK.

1,416,365.

Specification of Letters Patent. Patented May 16, 1922.

Application filed April 29, 1920. Serial No. 377,495.

To all whom it may concern:

Be it known that I, LARS J. LARSON, a citizen of the United States, and resident of the city of Seattle, county of King, and 5 State of Washington, have invented certain new and useful Improvements in Door Locks, of which the following is a specification.

My invention relates to improvements in 10 door locks, and more particularly to a mortise lock of the knob and key controlled type, having its bolt and actuating mechanism located within a tubular casing that may be mounted by being inserted and fixed within 15 a bored hole of like diameter.

The principal object of the invention is to 20 provide a lock of this character, which may be very easily applied, without the usual chisel work, and which will be serviceable, durable and possible to be manufactured at 25 a relatively small cost as compared to the cost of the usual type of mortise locks.

It is also an object of the invention to 30 provide both latch and knob controlled locks for the device which are of novel and simple construction.

In accomplishing these and other objects 35 of the invention I have provided the improved details of construction, the preferred forms of which are illustrated in the accompanying drawings, wherein—

Figure 1 is a longitudinal section, taken 40 vertically through the tubular casing of a lock embodying the present invention, as 45 mounted in a door; showing the bolt or latch extended into the latch opening of a door jamb.

Figure 2 is a similar horizontal section 50 of the same parts; also showing the knob and locking mechanism therein.

Figure 3 is a sectional view of the lock 55 from the side opposite that shown in Figure 1.

Figures 4 and 5 are vertical sections taken, 60 respectively, on the lines 4—4 and 5—5 of Figure 1.

Figure 6 is a sectional view of the door 65 knob taken on the line 6—6 of Figure 2.

Referring more in detail to the drawings: 70 1 designates a tubular casing wherein the principal parts of the lock are contained, and which at its outer end has a plate 2 secured thereto, adapted to receive screws, or the like, 3, to hold the lock in functioning 75 position when mounted in a door.

Fixed within the casing tube, at its inner

end, are bars 4 and 5, which are rounded on their outer sides to fit the walls of the tube, and have vertical, spaced apart adjacent faces, forming a longitudinal guideway 6, 60 wherein the inner end of a latch bolt 7 is slidably contained. At its outer end the bolt 7 has an extension or latch, 8, which is adapted to project through an opening 9 in the end plate 2, and into locking position within 65 the opening 10 of a plate 11 that may be fixed to the door jamb indicated at 12.

Outward movement of the latch is limited by the engagement of the outer end of the bolt 7 with the inner face of the plate 2, and 70 its movement into the casing is limited by the abutment of shoulders 13 and 14, respectively, at opposite sides and adjacent the outer and inner ends of the bolt, against the outer end of the bar 4 and a shoulder 15 75 formed centrally of the bar 5.

One face of the bolt 7 is provided with a longitudinally extending slot 17 wherein the forward end of the bar 5 is slidably contained, and interposed within this slot and bearing at its opposite ends against the forward end of the bar 5 and against the bolt 7 at the forward end of the slot 17, is a coiled spring 18 which yieldingly holds the bolt in extended position but which is adapted to yield and permit the bolt to move inwardly when the inclined face 8' of the latch moves into engagement with the edge of the plate 11, when the door is moved from open to closed position. 90

The means for drawing the bolt inwardly against the spring to release the latch from the jamb plate, comprises the usual knobs 20 that are fixed to the opposite ends of a square rod 21 which extends transversely 95 through the inner end of the lock housing, and which, within the lock, is contained within a sleeve 22 that is rotatably mounted in bores 23 transversely through the inner ends of the bars, 4 and 5, and which register 100 with a hole 24 transversely through the door. A semi-circular flange 25 is formed about the center of the sleeve 22, forming abutments 26, 26', at diametrically opposite upper and lower sides thereof, one of which 105 will, by turning the knob in either direction, be brought into engagement with laterally turned wings 27, 27', at the inner end of the bolt 7 to move the latter inwardly; the bolt being slotted, as at 28, to permit it to slide 110 inwardly beyond the sleeve 22.

On what would be the inner side of the

door, I have provided a locking device, comprising a knob 30 fixed at the inner end of a squared shaft 31 that extends transversely and revolvably through the lock, forward of its center, and which, within the lock, is contained within a sleeve 32 that may be rotated by the shaft within a transverse bore 33. Formed on the sleeve, between the bars 4 and 5, is an eccentric cam 35 which engages the under side of an arm 36 that is pivotally mounted at its inner end on a pin 37 extended between the bars and at its forward end is adapted, when the cam is in lowered position, to engage a shoulder 40 adjacent the forward end of the bolt 7 to hold the bolt against inward movement, but when the cam is turned partially around, it will raise the arm from the shoulder so that it is in position to pass into a slot 41 in the bolt and will not prevent its inward movement.

I have also equipped the outer knob 20 with locking mechanism whereby it may be prevented from being turned and in this manner the door can be locked from the outside. On this side of the door, shank 20' of the knob is rotatably contained within a sleeve 45, which is equipped with a base flange 46 whereby it is secured to the door and at its outer end extends within an annular slot 47 in the inner face of the knob.

The body of the knob is hollow, and located therein is a cross bar 48, provided at its ends with slots 49 which slidably receive ribs 50, formed on the inner walls of the knob, to lock the bar against rotative movement in the knob, but permitting it to move toward and from the base of the knob. This bar is enlarged at the center and provided with an opening 51 through which a key may be extended, as presently described, and on its inner side has extended fingers 52, 52', adapted to seat within notches 53, 53' in the outer end of the sleeve 45, to lock the bar and knob against turning and thereby prevent drawing of the bolt 7.

Located between the base of the knob and the bar 48, is an annular member 60 having a transverse portion 61 provided centrally with a boss 61', which is equipped with a key slot 62 formed in the center thereof and directly below the central opening 51 of the bar 48 and a key hole 63 in the center of the outer wall of the knob, into which a suitable key, as shown at 64, may be inserted to revolve the annular member 60.

The member 60 has two inclined surfaces 60' upon which the bar 48 rests, and when the member 60 is turned so that the bar is supported on the highest part of these surfaces,

the fingers 52, 52' will be raised free from the notches 53, 53', and the knob may be turned to move the bolt in the usual manner.

A coiled spring 70 is located within the knob to bear against the outer side of the bar 48 to hold the parts in functional position and urge the bar into locking relation when the member 60 is properly turned by the key, and dogs 71 are pivotally attached to the knob and urged inwardly by springs 72 into sockets 73 in the periphery of the ring member to hold the device yieldingly where placed by the key, either in unlocking or locking position.

With the lock so constructed, it is apparent that it can be mounted in a bored hole and secured in place by the end plate 2. Normally the bolt is held extended and can be drawn in by turning the knobs in either direction.

Locking from the inside can be done by manipulation of the knob 30, and from the outside by the key-actuated mechanism in the outer knob.

Such a lock is simple in construction, quick to install and will be serviceable and durable.

What I claim as new, is:

A door latch and lock comprising in combination a tubular casing, guide bars fixed in spaced relation within the casing at opposite sides thereof; said casing and bars having transverse bores therethrough adjacent their inner and outer ends, a bolt slidable longitudinally between the guide bars, having a latch head at its outer end and having laterally turned wings at its inner end, disposed at upper and lower sides of the inner end bore, also having slots longitudinally therein adapted to move in registration with said bores and having an abutment therein, a sleeve revoluble in the inner end bore having a semi-annular flange thereon providing abutments for engaging the said wings to move the bolt inwardly, an actuating rod for the sleeve, a spring engaging the bolt and normally retaining it in extended position, an arm pivotally mounted at one end between the guide bars and adapted to be moved at its opposite end into engagement with said shoulder to hold the bolt in extended position, a rod extended through the inner end bore of the casing, a cam fixed on said rod and adapted to be moved thereby to retain the locking arm from holding relation with the bolt.

Signed at Seattle, King County, Washington, this 22d day of April, 1920.

LARS J. LARSON.
